(57) CLAIM

We claim the ornamental design for a handheld vacuum cleaner, as shown and described.

DESCRIPTION

FIG. 1 is a top, front perspective view of a handheld vacuum cleaner showing our new design;

FIG. 2 is a top view thereof;

FIG. 3 is a right side view thereof; and,

FIG. 4 is a front view thereof.

The elements shown in broken lines are included for the purpose of illustrating environment and form no part of the claimed design.

1 Claim, 4 Drawing Sheets

FIG. 1

FIG. 4
